JOHN A. LUNGER, OF HIGH BRIDGE, NEW JERSEY.

MEANS FOR LOCATING AND GUIDING RAIL HOLDING AND LOCKING SPIKES.

1,193,280.

Specification of Letters Patent.

Patented Aug. 1, 1916.

Application filed May 28, 1914. Serial No. 841,421.

To all whom it may concern:

Be it known that I, JOHN A. LUNGER, a citizen of the United States, residing at High Bridge, in the county of Hunterdon and State of New Jersey, have invented certain new and useful Improvements in Means for Locating and Guiding Rail Holding and Locking Spikes, of which the following is a specification.

- 10 This invention has to do with the locking of rail holding spikes in railroad ties in an improved manner thereby to prevent them from working loose, the object of the invention being to provide improved means for 15 locating and guiding the rail-holding spikes and their locking spikes in the rail-supporting ties, whereby the use of intersecting spikes is made practicable in a very simple and efficient manner.
- 20 In the drawings accompanying and forming part of this specification, Figure 1 is a side view of a railroad rail and an end view of a tie thereof illustrating this improved means of locking a spike in position; Fig. 2 25 is a cross-sectional view of a rail and a side view of a spike; Fig. 3 is a top view of the improved means for holding and guiding the spike and its locking means; Fig. 4 is a front view thereof; Fig. 5 is a side view 30 looking from left to right of Fig. 4; and Fig. 6 is a view of the plate for holding the guiding means in position.

Similar characters of reference indicate corresponding parts throughout the several 35 figures of the drawings.

One of the most simple and effective ways of locking a railroad spike to prevent its working loose is to drive another spike or wedge horizontally through the tie so as to 40 intersect and pass through a hole in the rail holding spike, and while I am aware that railroad spikes have been used with holes therein, yet it has been attempted to hold these spikes in position by driving an interlocking pin into the tie at the same time the rail spike was driven down. In other words, the interlocking pin was driven along with the spike from the top of the tie and no attempt, so far as I am aware, has ever been 45 made to lock a spike in position by means of a pin subsequently driven from the side of a tie because of the difficulty and impracticability heretofore of so driving the interlocking spike as to properly intersect and pass through the rail holding spike, but by the present improvement I have successfully 50 driven in each instance the interlocking spike into position so that it will pass through the opening in the rail holding spike by the use of the improved guiding 55 means herein shown.

In the present improvement the spike 2 is provided with an elongated opening 3 which may be of any suitable size as occasion may require. The interlocking means 60 consists of a spike or wedge 4 driven horizontally through the tie 5 whereby the rail holding spike 2 is properly held in firm engagement with the flange 6 of the rail 7. This simple and efficient means of locking 65 a rail spike in position is, however, not practicable in use without the provision of the means herein shown which will permit the interlocking spike to be accurately driven 70 so as to pass through the opening in the rail holding spike. This means consists of a guide for the rail spike and of a guide for the interlocking spike combined in such manner as to fit around the tie during the driving of these spikes,—this guiding means 75 comprising an angular member 8 consisting 80 of a top plate 9 adapted to rest on top of the tie, and a side plate 10 adapted to engage the side of a tie. The top plate 9 is provided with a transverse slot 11 for the reception 85 of the shank of the rail holding spike and this slot terminates in a projection or stop 12 for guiding the rear side of the spike. At each side of the slot 11 the plate 9 is provided with a knife-edge projection 13 adapted to project between the bottom 90 of the rail flange and the tie. The side plate 10 is provided with a slot 14 and communicating therewith is a laterally extending grooved projection 15 for the reception 95 and guiding of the interlocking spike 4. For holding the guiding member 8 in proper position on a tie, a plate 16 may be used which may be held in position by suitable thumb screws or other fastening means. In use the 100 guide 8 is placed on a tie adjacent to the rail where it is desired to drive a spike with the plate 9 on top of the tie and the plate 10 at the side thereof and closely hugging the tie, the knife edges 13 being forced under the 105 rail so that the edges 17 of the guide plate 9 will contact with the side edge of the rail flange. The plate 16 is then clamped on top of the tie so that one of its edges will engage the edge 18 of the guide 8 and hold it 110 in position. The spike is then driven so that it will pass through the slot 11 with its head

in contact with the stop 12. Then the interlocking spike is placed in the grooved guide 15 and driven horizontally through the tie whereupon, as has been found in practice, 5 the interlocking spike will be accurately driven so as to intersect the slot 3 of the rail holding spike.

From the foregoing it will be observed that the guide for the locking spike extends 10 transversely to the guide for the rail holding spike, so that by the present improvement is made possible the use of an interlocking spike which may be driven through the side of the tie so as to interlock the rail 15 holding spike and prevent it from working loose.

It will be understood that the various details may be more or less modified without departing from the spirit or scope of the 20 present improvement.

I claim as my invention:—

1. Means for locating and guiding a pair of spikes while being driven into a railroad tie, one spike having an opening therein and 25 being guided to enter from the top of the tie and the other spike being guided to enter from the side of such tie and pass into the opening in the first spike, said means independent of and removable from said tie after 30 the interlocking of the spikes and before both spikes have been completely driven and comprising a part for determining the position of and directing the rail-holding spike as it passes into said tie from the top 35 thereof and a part for determining the position of and directing the spike during a part of the driving thereof as it passes through the side of the tie and into the opening of the rail-holding spike.

40 2. A device for insuring the driving of an interlocking spike through the side of a railroad tie so as to project into an opening of a rail-holding spike passing into the top of such tie, said device consisting of a guide 45 for the rail-holding spike and a guide for the interlocking spike, said first guide comprising a slotted plate having a spike-guiding stop and having one or more knife edges for insertion under the rail.

50 3. A device for insuring the driving of an interlocking spike through the side of a railroad tie so as to project into an opening of a rail-holding spike passing into the top of such tie, said device consisting of a guide 55 for the rail-holding spike and a guide for the interlocking spike, said second guide comprising a plate having a recess and a laterally extending member having a groove in its side to guide the interlocking spike.

60 4. A device for insuring the driving of an interlocking spike through the side of a railroad tie so as to project into an opening of a rail-holding spike passing into the top of such tie, said device consisting of a guide 65 for the rail-holding spike and a guide for

the interlocking spike, said first guide comprising a slotted plate having a spike-guiding stop and said second guide comprising a plate having a recess and a laterally extending member having a spike-guiding groove 70 in its side.

5. A device for insuring the driving of an interlocking spike through the side of a railroad tie so as to project into an opening of a rail-holding spike passing into the top of such tie, said device consisting of a guide for the rail-holding spike and a guide for the interlocking spike, said first guide comprising a slotted plate having a spike-guiding stop and one or more knife edges for insertion under the rail and said second guide comprising a plate having a recess and a laterally extending member having a spike-guiding groove 75 in its side.

6. A device for insuring the driving of an interlocking spike through the side of a railroad tie so as to project into an opening of a rail-holding spike passing into the top of such tie, said device consisting of a guide for the rail-holding spike and a guide for the interlocking spike, said first guide comprising a slotted plate having a spike-guiding stop and one or more knife edges for insertion under the rail and said second guide comprising a plate having a recess and a laterally extending member having a spike-guiding groove 80 in its side, and means for holding said guiding means against the rail.

7. A device for insuring the driving of an interlocking spike through the side of a railroad tie so as to project into an opening of a rail-holding spike passing into the top of such tie, said device consisting of a guide for the rail-holding spike and a guide for the interlocking spike, said first guide comprising a slotted plate having a spike-guiding stop and one or more knife edges for insertion under the rail and said second guide comprising a plate having a recess and a laterally extending member having a spike-guiding groove 90 in its side, and means for holding said guiding means against the rail.

105 8. A device for insuring the driving of an interlocking spike through the side of a railroad tie so as to project into an opening of a rail-holding spike passing into the top of such tie, said device consisting of a guide for the rail-holding spike and a guide for the interlocking spike, said guides extending transversely to each other and each consisting of a slotted member, and a clamping plate for holding said guides in position.

115 9. A railroad - rail - spike - guiding means 120 comprising an angularly formed guiding member adapted to extend along two sides of a railroad tie, each part thereof having means for guiding and directing a spike during a part of the driving thereof while 130

said angular guiding means is in position on a railroad tie so that one spike may be driven through the side of the tie to interlock with the rail-holding spike driven through the 5 top of the tie, said means being removable after the interlocking of the spikes and before both spikes have been completely driven.

10. A railroad rail spike-guiding means comprising an angularly formed guiding member adapted to extend along two sides of the tie, one part thereof comprising a horizontal member having a slot for the reception of a rail-holding spike and a 15 pending member having a laterally extending projection grooved in one side for the reception of an interlocking spike.

11. A railroad rail spike-guiding means comprising a horizontal plate and an 20 upright plate, said horizontal plate having a

spike-guiding stop and a slot for the reception of a spike and said upright plate having a laterally extending member grooved in its side for the reception of a spike, so that one spike may be driven to intersect 25 the other.

12. Spike guiding means comprising an angular plate, one part thereof having a slot terminating in a stop for the reception of a rail spike and having one or more knife 30 edges to assist in holding the plate in position, and the other part having a slot and a laterally extending grooved projection in alinement with said slot for the reception of a spike, so that one spike may be driven to 35 intersect the other.
